UNITED STATES PATENT OFFICE.

FELIX KOCH, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

VESTIBULE GUARD FOR ARTICULATED CARS.

Application filed March 2, 1926. Serial No. 91,826.

This invention relates to articulated cars and has for an object the provision of safety means between the interior portions of the adjacent ends of two adjacent bodies and the movable vestibule or passageway member therebetween.

Another object of the invention is to provide an automatically adjustable safety means between the interior portions of the adjacent ends of the adjacent bodies of an articulated car and the vestibule or passageway member therebetween.

A further object of the invention is to provide an adjustable guard for an articulated car which is located interiorly of the car and which extends between and is attached at one end to the end portion of the car body and at the other end to a vestibule or passageway member.

These and other objects will be apparent from the following description:

Referring to the drawings in which like reference characters refer to like parts, Fig. 1 is a cross sectional view of a portion of an articulated car embodying the invention; Fig. 2 is an enlarged plan sectional view taken on the line 2-2 of Fig. 1; Fig. 3 is a view similar to Fig. 2 and illustrates a modification of the invention, and Figs. 4 and 5 are diagrammatic plan views showing the invention in several of its operating positions.

Referring now in detail to the drawings the reference character 1 indicates an articulated car which comprises a plurality of bodies 2 which are of any suitable construction.

Between the adjacent ends of two adjacent car bodies, and between the vertically disposed posts or framing members 3 of such ends there is arranged a vestibule or passageway member 4. This member 4 is preferably of cylindrical form and is mounted either on the truck or upon one of the bodies 2 in such a manner that relative rotary movement between the member and the adjacent ends of the bodies 2 is permitted. This member 4 has a passageway 5 formed therethrough and adjacent each side of such passageway the curved sides 6 of the member 4 are engaged by weatherproofing elements 7 which are mounted on the posts 3 of the adjacent ends of two adjacent bodies. In the present embodiment of the invention

these elements 7 are in the form of rollers 55 but it will be understood that any other suitable weatherproofing elements may be used.

The edges of the walls 6 of the vestibule member which form the passageway 5 are within the car bodies at all times but the 60 relative positions of these edges and the weatherproofing elements are being varied substantially all the time the car is in transit and it would be possible for a passenger's clothing to be accidentally drawn into the 65 spaces between the walls 6 and the posts 3 or between the walls 6 and the weatherproofing elements 7 with the consequent damage to the clothing. Further a passenger could be injured by having his hand 70 or other part of his body squeezed between the walls 6 and the posts 3 or between the walls 6 and the weatherproofing elements 7. For the purpose of preventing any accidents of the nature just referred to, guard 75 means 8 are provided between the vestibule member and the posts 3. These guard means may be of any suitable form but as illustrated in the drawings each preferably comprises a flexible member, one edge portion of which is attached to the vestibule member adjacent the edge defining a portion of a passageway 5 and the opposite edge portion being attached to the adjacent car body. This member may extend in a 80 vertical direction for the full length of the sides 6 of the vestibule member or if desired may be made of less length. Between the edge portions which are attached to the vestibule member and the post 3 this member is plaited so that it is adjustable and can be lengthened or shortened automatically as the relative position of the car body and the vestibule member varies, thus effectively 85 covering the space between the vestibule 90 member and the post 3.

In Fig. 3 of the drawings a modification of the guard member 8 has been illustrated which comprises a curtain 9, a portion of which is rolled on a spring controlled roller 100 (not shown) mounted within a casing 10 secured to the body of the car. The free end of this curtain is attached to the vestibule member. In this modification it will be understood that if desired the curtain roller 105 may be mounted on the vestibule member and the free end of the curtain may be attached to the car body.

Having thus described the invention what I claim as new and desire to secure by Letters Patent is:—

1. In an articulated car comprising a plurality of bodies, a vestibule member between the adjacent ends of two of said bodies, weather proofing means between said member and bodies, and guard means extending between said member and bodies across the point of contact of said weather proofing means interiorly of said bodies.
  2. In an articulated car comprising a plurality of bodies, a vestibule member between the adjacent ends of two of said bodies, weather proofing means between said member and said bodies, and automatically adjustable guard means extending between said member and bodies interiorly of said bodies, adapted to prevent accidental access to said weather proofing means.
  3. In an articulated car comprising a plurality of car bodies, a vestibule member between the adjacent ends of two of said bodies, weather proofing means intermediate the sides of said member and said bodies, and guard means arranged interiorly of said bodies for covering the spaces between said bodies and vestibule member.
  4. In an articulated car comprising a plurality of car bodies, spaced vertical posts for each of said bodies, a vestibule member for said bodies adapted to extend between the post of each body weather proofing means on said bodies bearing on said vestibule member, and a guard member interiorly of each of said bodies spanning the space between each of the posts of each of said bodies and said vestibule member.
  5. In an articulated car comprising a plurality of car bodies, a vestibule member between the adjacent ends of two of said
- bodies, said member having portions extending into said bodies, weather proofing means between said portion of said member and said bodies, and guard means secured to the portions of said member that are within said bodies and extending therefrom to the said bodies and there secured.
- 45
6. In an articulated car comprising a plurality of car bodies, a vestibule member between the adjacent ends of two of said bodies having a passageway formed therein, weather proofing means between said bodies and said vestibule, and guard members within said bodies extending from said vestibule member to adjacent parts of said bodies and secured thereto, each of said guard members being secured to said vestibule member adjacent one side of said passageway to prevent accidental access to the space between said vestibule member and ends of said bodies.
- 50
7. The combination with the adjacent ends of two bodies of an articulated car, of a vestibule member between said bodies, said member having portions extending into said bodies, and a guard member extending between and attached to each of said portions and the adjacent portion of one of said bodies.
- 55
8. The combination with the adjacent ends of two bodies of an articulated car, of a vestibule member between said ends, said member comprising curved sides which terminate interiorly of said bodies, weather proofing means between adjacent sides of vestibule member and car bodies, and a guard member secured to said curved sides and extending therefrom to adjacent part of said body.
- 70
- 75
- In testimony whereof I affix my signature.
- FELIX KOCH.
